WIRE RACK

Walter Dean, Winnipeg, Manitoba, Canada, assignor of one-half to Herbert Richard, Winnipeg, Manitoba, Canada

Application January 28, 1947, Serial No. 724,896

2 Claims. (Cl. 220—19)

2

This invention relates to machines for washing dishes and the like. An object of the invention is to provide an attachment for clothes-washing machines by means of which they may be used for washing dishes.

Another object of the invention is to provide a support for dishes and silverware, which may be placed into an agitator type clothes-washing machine, and, when dishes have been placed in the support the machine may have a quantity of water placed therein with a little soap or soap powder to wash the dishes.

A further object of the invention is to provide a dishwashing attachment for clothes-washing machines, which is simple in design, inexpensive to manufacture, and which is effective in operation, and which may be installed as needed, without making any alterations in the clothes-washing machine.

Other objects and advantages of the invention will become apparent from the following description of a preferred embodiment thereof as illustrated in the accompanying drawings, and in which:

Figure 1 is a sectional elevation of a portion of a clothes-washing machine, with my improved device disposed therein.

Figure 2 is a plan view of the wire rack shown in Figure 1, but apart from the washing machine, and

Figure 3 is a plan view of that element of my improved device which is employed for holding articles in the nature of knives, forks and spoons.

Reference may now be had to the drawings, in which like reference characters denote similar parts throughout the several views. As shown, there is a washing machine generally indicated at 2, and including a suitable support, not shown, upon which is mounted a tub 4 having a bottom 6 and a cylindrical side wall 8. The upper edge of the wall 8 is flanged at 10 to form a seat for a cover member 12 having a handle 14 for removing the cover to afford access to the inside chamber 16 of the tub.

The bottom 6 of the tub has a boss 18 with an axial bore 20 through which extends the operating shaft 22 of an agitator 24, the latter being disposed within the tub chamber 16, and the lower end of the shaft 22 being connected to a suitable drive mechanism including a motor, not

shown. The agitator 24 has an upstanding central portion 26, with fins 28 radiating therefrom, in order to agitate the water and soap inside the chamber 16 as the agitator rotates or oscillates about the axis of the shaft 22.

In order to wash dishes and silverware in the same washing machine and tub 8, I provide a support which may be disposed within the chamber 16 and which carries the dishes and silverware. My support is stationary relative to the tub 8, and supports the dishes within the chamber 16 in such manner as to receive upon the dishes and silverware the water and soap, or soapy water as it is agitated by the agitator 24, thus cleansing them.

For this purpose I provide a rack indicated generally at 30 and formed preferably of relatively heavy wire rods. As shown, my rack includes a number of substantially U-shaped elements 32 formed of wire rods bent as shown, and fastened together to form the rack. One type of element 32 is formed of wire rod extending vertically from location 34 to 36, thence inclined outward from location 36 to 38, thence bent between locations 38 and 40 to lie substantially parallel to and upon the bottom member 6. The element 32 is then bent upward between locations 40 and 42, and then is bent to lie substantially parallel to bottom 6 between locations 42 and 44, and then is bent upward between locations 44 and 46 substantially parallel to the portion between locations 34 and 36. The two ends of the element 32 are thus located at 34 and 46.

Another type of element 48 is similar in form to the elements 32, except that they do not extend all the way down to the bottom 6 of the tub as do the elements 32. Thus an element 48 has a portion commencing at 50 and extending downward to location 52, whence it flares outward between locations 52 and 54, being bent from locations 54 to 56 substantially parallel to the tub bottom 6 although spaced therefrom, as best shown in Figure 1. It is then bent upward between locations 56 and 58 and then again bent to lie substantially parallel to bottom 6 between locations 58 and 60. Between locations 60 and 62 is bent upward substantially parallel to the portion lying between locations 50 and 52.

The rack elements 32 and 48 are all connected 50 at their outer ends 34 and 50 respectively to an

upper outer ring 64 the diameter of which is almost as great as that of the inside of the tub chamber 16, and the elements are connected at their inner ends 46 and 62 respectively to an upper inner ring 66. A lower outer ring 68, similar in size to ring 64, has all the elements 32 and 48 secured to it at their locations 36 and 52 respectively. A lower inner ring 67 is installed below ring 66, being of the same size and connected to the same elements but lower down. All connections mentioned may be formed by welding.

It is thus apparent that the elements 32 and 48 are thus assembled with the rings 64, 66 and 68, into a rack or basket-like support for dishes and the like, with substantially cylindrical outer walls below the ring 64 and substantially cylindrical inner walls below the ring 66, the elements being bent respectively from locations 42 to 44 and locations 58 to 60 to form, when assembled, an annular inner shelf or ledge 72. And it will be further noted that some of the elements, namely those denoted 32 are bent between locations 33 to 40 to form a first shelf or support for the rack, resting upon tub bottom 6, and that other of the elements, namely those denoted 48, are bent between locations 54 and 56 to form a second shelf portion 72 spaced from and lying above the tub bottom 6 and the element portions between locations 33 and 40. There may be several elevated shelf portions 72, depending upon the number and arrangement of the elements 48, and these shelf portions 72 are suitable for supporting glasses open end downward, and also for supporting a curved silverware container or rack 74 shown in Figures 1 and 3, in elevation and plan.

The rack 74 is also formed of wire rod, and has a number of U-shaped members 76 connected along their bottoms by curved bottom members 78 bent upward at the ends, and connected along their sides and tops by encircling members 80 and 82 to form an upwardly open chamber 84 inside the rack for the reception of silverware.

It will be observed that the locations of the upright bent portions of the elements 32 and 48 between locations 40 and 42 and between locations 56 and 58 respectively, are such as to allow ample clearance for the agitator or impeller vanes 23 to move freely without touching the rack, and also that the diameter of the ring 66 and the cylindrical chamber formed therebelow is large enough to avoid touching any part of the upstanding portion 26 of the agitator.

In use, it is only necessary to place the rack into the chamber 16 of the tub, and place the dishes, glassware, and silverware in position as already described and illustrated, the plates 86 being stacked as shown in Figure 1. Then water and soap powder are placed in the tub chamber 16 and agitated until the dishes are clean. The soapy water is then removed from the tub and fresh rinsing water placed therein, which will rinse the dishes as the agitator operates.

To use the machine for washing clothes, it is only necessary to remove the rack therefrom, and proceed in the usual manner to wash the clothes.

Although I have described a preferred embodiment of my invention in specific terms, it is to be understood that various changes may be made in size, shape, materials and arrangement without departing from the spirit and scope of the invention as claimed.

I claim:

1. A rack for support within a washing machine tub comprising a first pair of horizontally disposed rings positioned in superimposed spaced

relation with respect to each other, a second pair of horizontally disposed rings arranged in superimposed spaced relation and positioned so that the upper one of said rings is wholly within and spaced from the upper one of said first pair of rings and the lower one of said rings is wholly within and spaced from the lower one of said first pair of rings, a first plurality of upstanding U-shaped rods arranged in spaced relation about a portion of said first and second pairs of rings, each of said rods having the free end of one leg secured to the upper one of said first pair of rings and the free end of the other leg secured to the upper one of said second pair of rings, the bights of said first plurality of rods together forming a first shelf adapted to rest upon the floor of a washing machine tub, the legs of each of said rods being also secured respectively to the lower ones of said first and second pairs of rings, and a second plurality of upstanding U-shaped rods arranged in spaced relation about the remaining portion of said first and second pairs of rings and each having the free end of one leg secured to the upper one of said first pair of rings and the free end of the other leg secured to the upper one of said second pair of rings, the bights of said second plurality of rods together forming a second shelf spaced above said first shelf, the other legs of said second plurality of rods being also secured respectively to the lower ones of said first and second pairs of rings.

2. A rack for support within a washing machine tub comprising a first pair of horizontally disposed rings positioned in superimposed spaced relation with respect to each other, a second pair of horizontally disposed rings arranged in superimposed spaced relation and positioned so that the upper one of said rings is wholly within and spaced from the upper one of said first pair of rings and the lower one of said rings is wholly within and spaced from the lower one of said first pair of rings, a first plurality of upstanding U-shaped rods arranged in spaced relation about a portion of said first and second pairs of rings, each of said rods having the free end of one leg secured to the upper one of said first pair of rings and the free end of the other leg secured to the upper one of said second pair of rings, the bights of said first plurality of rods together forming a first shelf adapted to rest upon the floor of a washing machine tub, the legs of each of said rods being also secured respectively to the lower ones of said first and second pairs of rings, and a second plurality of upstanding U-shaped rods arranged in spaced relation about the remaining portion of said first and second pairs of rings and each having the free end of one leg secured to the upper one of said first pair of rings and the free end of the other leg secured to the upper one of said second pair of rings, the bights of said second plurality of rods together forming a second shelf spaced above said first shelf, each of the other legs of said first and second plurality of rods having a portion extending from and terminating at a point spaced from the bight offset, said portions together forming a ledge adapted to overlie an upstanding agitator which may be a part of said washing machine tub.

WALTER DEAN.
